FOUR-IN-HAND NECKTIE

Application filed April 5, 1930. Serial No. 441,827.

My invention relates to an improvement in four-in-hand neckties.

The object of my invention is to provide a lining for a four-in-hand necktie which is 5 made of a plurality of layers of live springy cloth cut to fit accurately the confines of a silk or other envelope comprising the exterior portion of the necktie, and to so cut the material comprising the layers of lining that the 10 tendency of each layer to assume a flat position inside an envelope will force the material of the envelope to assume a smooth neat appearance.

More particularly stated, it is the object of 15 my invention to cut the various layers of lining material for a necktie in opposite directions of the original piece of lining material whereby to provide in a lining construction for a necktie, at least one layer cut with the 20 warp of the goods and one layer cut with the woof of the same or similar piece so that the internal tension of the various plies of lining material will compensate one another to carry out the general object of my invention which 25 is to provide a lining which will most efficiently and practically assist in maintaining the envelope or covering of the tie in smooth condition.

In the drawings:

30 Figure 1 is a plan view of the inner face of a necktie made in accordance with my invention, a portion of the seam of the tie being open to exhibit my tie lining.

Figure 2 is a plan view of one layer of my 35 tie lining.

Figure 3 is a plan view of another ply of the lining.

Figure 4 is an isometric view of a portion 40 of my tie showing a cross section in detail.

Like parts are identified by the same reference characters throughout the several views.

I am aware that many attempts have been made to provide a four-in-hand tie construction 45 wherein a lining is provided to assist in maintaining the general ensemble of the tie in smooth neat condition, but the particular construction which I have shown in the drawings and herein described has been found to accomplish this purpose more efficiently and ex-

peditiously than any lining construction of which I am aware.

Conforming to the general external appearance of the usual four-in-hand tie, I provide an envelope or casing 10 of silk or other 55 suitable material folded along lines 11 and 12 to provide defined margins of the body of my tie and at 13 I fold the envelope so that by means of stitching 14 a fairly rigid seam completes the closure of the flattened tubular 60 covering.

Within the casing or covering I place the various plies of the lining which is so important in the construction of my tie and I form these plies as indicated in Figures 2 and 65 3 where it will be seen that one of the plies 15 is cut with the warp, in other words, lengthwise of the piece, and another ply 16 as shown in Figure 3 is cut with the woof, or crosswise of the piece. Other plies cut in 70 other directions of the piece may be added, but I have found that a combination of plies, one or more of which is cut lengthwise and another cut crosswise of the piece, constitute 75 a complete combination which will effectively secure the results which I endeavor to obtain.

The two plies 15 and 16 of lining material when cut to conform to the lines 11 and 12 of the envelope may be superimposed upon one 80 another and folded in the envelope as indicated in that portion 17 of the necktie shown in Figure 1.

By stitching or otherwise closing the envelope 10, I have found that in conformity 85 with the spirit of my invention it is preferable to only stitch one layer, for instance the ply 15 of the lining, to the envelope as indicated in Figures 1 and 4 so that the plies of lining and particularly the margins thereof 90 are free to straighten out after they have been folded or formed in the usual convolutions necessary to the formation of a four-in-hand tie as worn.

Marginally the plies constituting the lining 95 of my tie, conforming as they do to the lines 11 and 12, force the covering 10 of the tie to assume as flat and smooth an appearance as the lining itself and I have found that in all instances the linings will maintain their rela- 100

tion with respect to each other as shown in the drawings.

Choice of material from which to cut the lining plies is, of course, important and I have found that a layer of a wool material and a layer of mohair cloth is preferable since wool and mohair cloth have a tendency to resist creasing and tend to remain live, active and springy under all conditions.

10 A person wearing my tie will find after he has removed it following a day's wear that the various creases formed by the knot and the curling of the material will slowly disappear as the material of the lining pulls, 15 stretches, strains and pushes inside the confines of the casing 10, and after a short time the resultant forces will be found to have straightened and flattened the covering and completely eradicated creases caused by its 20 use and the tie will be found to be in substantially unimpaired condition.

I claim:

The combination with a necktie casing folded to provide defined margin lines, of 25 lining material for said casing comprising a plurality of layers of woven fabric containing wool and shaped to conform to said margin lines, one of said layers being cut with the warp and another being cut with the 30 woof of its material.
